(57) **CLAIM**

The ornamental design for an obelisk columbarium structure, as shown and described.

DESCRIPTION

FIG. 1 is a perspective view of a first embodiment of the obelisk columbarium structure of the present design.

FIG. 2 is a front elevation view of the obelisk columbarium structure of FIG. 1. The rear elevation view is the same as the front elevation view.

FIG. 3 is a left side elevation view of the obelisk columbarium structure of FIG. 1. The right side elevation view is the same as the left side elevation view.

FIG. 4 is a top plan view of the obelisk columbarium structure of FIG. 1.

FIG. 5 is a perspective view of a second embodiment of the obelisk columbarium structure of the present design.

FIG. 6 is a front elevation view of the obelisk columbarium structure of FIG. 5. The rear elevation view is the same as the front elevation view.

FIG. 7 is a left side elevation view of the obelisk columbarium structure of FIG. 5. The right side elevation view is the same as the left side elevation view.

FIG. 8 is a top plan view of the obelisk columbarium structure of FIG. 5.

FIG. 9 is a perspective view of a third embodiment of the obelisk columbarium structure of the present design.

FIG. 10 is a front elevation view of the obelisk columbarium structure of FIG. 9. The rear elevation view is the same as the front elevation view.

FIG. 11 is a left side elevation view of the obelisk columbarium structure of FIG. 9. The right side elevation view is the same as the left side elevation view.

FIG. 12 is a top plan view of the obelisk columbarium structure of FIG. 9.

FIG. 13 is a perspective view of a fourth embodiment of the obelisk columbarium structure of the present design.

FIG. 14 is a front elevation view of the obelisk columbarium structure of FIG. 13. The rear elevation view is the same as the front elevation view.

FIG. 15 is a left side elevation view of the obelisk columbarium structure of FIG. 13. The right side elevation view is the same as the left side elevation view.

FIG. 16 is a top plan view of the obelisk columbarium structure of FIG. 13.

FIG. 17 is a perspective view of a fifth embodiment of the obelisk columbarium structure of the present design.

FIG. 18 is a front elevation view of the obelisk columbarium structure of FIG. 17. The rear elevation view is the same as the front elevation view.

FIG. 19 is a left side elevation view of the obelisk columbarium structure of FIG. 17. The right side elevation view is the same as the left side elevation view.

FIG. 20 is a top plan view of the obelisk columbarium structure of FIG. 17.

FIG. 21 is a perspective view of a sixth embodiment of the obelisk columbarium structure of the present design.

FIG. 22 is a front elevation view of the obelisk columbarium structure of FIG. 21. The rear elevation view is the same as the front elevation view.

FIG. 23 is a left side elevation view of the obelisk columbarium structure of FIG. 21. The right side elevation view is the same as the left side elevation view.

FIG. 24 is a top plan view of the obelisk columbarium structure of FIG. 21.

FIG. 25 is a perspective view of a seventh embodiment of the obelisk columbarium structure of the present design.

FIG. 26 is a front elevation view of the obelisk columbarium structure of FIG. 25. The rear elevation view is the same as the front elevation view.

FIG. 27 is a left side elevation view of the obelisk columbarium structure of FIG. 25. The right side elevation view is the same as the left side elevation view.

FIG. 28 is a top plan view of the obelisk columbarium structure of FIG. 25.

FIG. 29 is a perspective view of an eighth embodiment of the obelisk columbarium structure of the present design.

FIG. 30 is a front elevation view of the obelisk columbarium structure of FIG. 29. The rear elevation view is the same as the front elevation view.

FIG. 31 is a left side elevation view of the obelisk columbarium structure of FIG. 29. The right side elevation view is the same as the left side elevation view; and,

FIG. 32 is a top plan view of the obelisk columbarium structure of FIG. 29.

The dashed lines depict environment and portions of the obelisk columbarium structure that form no part of the claimed design.
